H. S. McCORMACK.
TYPE WRITING MACHINE.
APPLICATION FILED NOV. 6, 1908.

921,620.

Patented May 11, 1909.

UNITED STATES PATENT OFFICE.

HARRY S. McCORMACK, OF NEW ROCHELLE, NEW YORK; ASSIGNOR TO UNDERWOOD TYPEWRITER COMPANY, OF NEW YORK, N. Y., A CORPORATION OF NEW JERSEY.

TYPE-WRITING MACHINE.

No. 921,620.

Specification of Letters Patent.

Patented May 11, 1909.

Application filed November 6, 1908. Serial No. 461,412.

To all whom it may concern:

Be it known that I, HARRY S. McCORMACK, a citizen of the United States, residing in New Rochelle, in the county of Westchester and State of New York, have invented certain new and useful Improvements in Type-Writing Machines, of which the following is a specification.

This invention relates to card guides or feeders for typewriting machines.

In order to enable the types to make clear impressions, it is necessary for a card or paper to lie close against the platen at the printing point; but stiff paper or cards tend to bulge out between their side edges to an extent to cause the writing to be blurred. Such bulging is largely due to the flexing of the card around the cylindrical platen, as the card tends constantly to spring back from its flexed condition to its normal flat shape, thus causing a bulge wherever the card is not tightly held by its guides against the platen. It is also found difficult to feed cards properly around the platen, owing to their stiffness and resistance to being bent around the same. Largely for these reasons, it has been found difficult to write upon stiff cards clearly, especially at their edges, and particularly at their bottom edges.

The principal object of this invention is to overcome these objections, and make it practicable to feed a card accurately in line-space direction, and to write clearly upon all parts of the same, including all edge portions.

In carrying out the invention, in addition to the usual card-pressing rolls which run upon the platen, I provide an auxiliary feeding device directly above the printing line in a front strike machine, whereby the card is drawn up from the printing line. This auxiliary device comprises a feeding roll, out of contact with the platen, but driven by a driving roll or rolls which run directly upon the platen. The top edge of the card as it rises above the printing line enters the bite of this auxiliary feeding device, which turns at the same surface speed as the platen, and for some distance co-operates with the platen and the usual platen pressure rolls to advance the card. After the bottom edge of the card has passed the usual platen pressure rolls, the auxiliary feeding device is relied upon to draw the card up line by line until it is filled with writing. The line feeding of the card is thus always positive and accurate.

A further advantage is derived from permitting the card as it passes up from the printing point to resume substantially its flat or unbent normal condition, whereby its tendency to bulge is materially reduced, and when the bottom edge of the card advances to the printing line, the tendency to bulge disappears, because the entire card at this time is in a substantially flat unsprung condition, and writing may be accurately and clearly done right along its very bottom edge. This flat or normal condition in the card also conduces to accuracy in the line-feeding of the auxiliary feeding devices.

Other objects and advantages will hereinafter appear.

In the accompanying drawings, Figure 1 shows side and edge views of the main structure of one of the principal members of the auxiliary feeding devices. Fig. 2 is a part sectional side elevation of the platen and platen frame of an "Underwood" front strike writing machine, to which my improvements have been applied; one of the auxiliary feed arms being shown swung up from the platen. Fig. 3 is a perspective view of said platen and platen frame, showing the auxiliary feed mechanism; a card being shown by dotted lines.

Types 1, mounted in a segment 2, strike against the front side of a platen 3, mounted in the ends 4 of a platen frame, which also comprises a rear paper shelf 5, and is advanced in line-space direction by a lever 6, pawl 7 and a ratchet wheel 8. Rear and front rolls 9, 10 run upon the under side of the platen, and the paper shelf 5 curves forwardly around the bottom of the platen, and up at the front side thereof nearly to the printing line, as at 11.

The card A is introduced between a pair of gages 12 for its side edges, said gages running down along the paper shelf 5, and prolonged at 13 to extend between the platen and the paper shelf nearly to the pressure roll 9; the card being thus guided until it enters the bite of the pressure roll and platen, is not liable to become skewed. The card feeds forwardly around the under side of the platen, and up in front thereof, and is written upon by the types 1. The card is held back against the platen by a guard 14 inserted in the top of the type bar segment 2, said guard in the form of a yoke or bow surrounding the printing point just back of the ink ribbon 15. In

said Underwood machine, the platen frame travels from left to right for letter-spacing, being provided with a roll 16 to run upon a rail 17, said roll pivoted upon a rod 18 forming part of the platen frame. During this letter-spacing travel of the carriage, the card travels while the guard 14 remains stationary, the latter serving to hold the card firmly at the printing point.

10 From the printing line the card passes up behind a pair of directrices 19 (which extend down in front of the card 14) to a pair of feeding rolls 20, which are turned by means of driving rolls 21 that run upon the surface of the platen, so that the surface speed of the feeding rolls 20 is always the same as that of the platen. The card is held against the feeding roll 20 by spring clips 22 with sufficient force to enable the rolls to advance the card upwardly; and the directrices 19 may be in the form of pendent forwardly offset extensions of said spring clips, as shown. As the platen turns, the card is carried up by the rolls 10, 20 in coöperation, until the bottom edge of the card passes the roll 10, whereupon the rolls 20, which together with the clips 22 form the auxiliary feeding device, form the sole means for advancing the card. At this time, the card is nearly in normal flat condition, and as the card rises line by line this condition is more nearly approximated, until at the writing of the final line, which may be close to the bottom edge of the card, the latter is substantially flat and devoid of tendency to bulge away from the platen.

15 The auxiliary feeding devices 19 to 22 are mounted upon the forward ends of a pair of arms 23 which extend rearwardly over the platen, and at their rear ends are hinged at 24 to the side-gage plates 12; the latter being fixed to slides 25 which are adjustable independently of each other lengthwise of the platen along a rod 26 fixed to the platen frame ends; the slides 25 being prevented 20 from turning on the rod by keys 27 of common construction.

25 The hinging of the arms permits them to be swung backwardly away from the platen, as seen at the upper part of Fig. 2; and a further object of hinging them is to enable them to be adjusted to cause the guide rolls 21 to press firmly upon the platen. This pressure is produced by screws 28 threaded through the arms at points forward of the 30 hinges, and bearing against beveled faces 29 upon the supporting plates 12; the bevels being so inclined that pressure of the screw points thereagainst forces the arms 23 to swing downwardly toward the platen. The 35 pressure of the driving rolls may thus be nicely regulated. Upon unscrewing either of the screws 28 its arm may be swung up above the hinge 24 to the position seen at the top of Fig. 2.

40 A further object accomplished by this in-

vention resides in reducing the extent to which the card is bent around the platen, since in front strike writing machines it has usually been necessary to bend the cards nearly around the entire platen, whereby 45 the cards have acquired a permanent set, which set proves an objection where the written cards are used for card indexes. This objection is overcome because a card is bent around only a small portion of the 50 platen, and all portions of the card are not bent at the same time, so that the card in emerging from the machine is in substantially normal flat condition well adapted for 55 card index work.

60 Variations may be resorted to within the scope of the invention, and portions of the improvements may be used without others.

Having thus described my invention, I claim:

1. In a typewriting machine, the combination with a revoluble platen and a platen frame, of a rod mounted on the platen frame and extending along the platen, an arm extending from said rod toward the printing line on the platen, a driving roll pivoted on said arm to run upon the surface of the platen, and means mounted on said arm and including a feeding roll operated by said driving roll, for feeding cards forwardly from 95 the printing line.

2. In a typewriting machine, the combination with a revoluble platen and a platen frame, of a rod mounted on the platen frame and extending along the platen, an arm extending from said rod toward the printing line on the platen, a driving roll pivoted on said arm to run upon the surface of the platen, and means mounted on said arm and including a feeding roll operated by said driving roll, for feeding cards forwardly from 100 the printing line; said arm carried on a slide 105 mounted on said rod.

3. In a typewriting machine, the combination with a revoluble platen and a platen frame, of a rod mounted on the platen frame and extending along the platen, an arm extending from said rod toward the printing line on the platen, a driving roll pivoted on said arm to run upon the surface of the 115 platen, and means mounted on said arm and including a feed roll operated by said driving roll, for feeding cards forwardly from the printing line; said arm having provision for regulating the pressure of the driving roll 120 against the platen.

4. In a typewriting machine, the combination with a revoluble platen and a platen frame, of a rod mounted on the platen frame and extending along the platen, an arm extending from said rod toward the printing line on the platen, a driving roll pivoted on said arm to run upon the surface of the platen, means mounted on said arm and including a feeding roll operated by said driv- 130

- ing roll, for feeding cards forwardly from the printing line, said arm pivoted upon a slide mounted upon said rod, a screw working between said arm and slide, and means coöperating with said screw to swing the arm toward the platen. 70
5. In a typewriting machine, the combination with a revoluble platen and a platen frame, of a rod mounted on the platen frame and extending along the platen, an arm extending from said rod toward the printing line on the platen, a driving roll pivoted on said arm to run upon the surface of the platen, means mounted on said arm and including a feeding roll operated by said driving roll, for feeding cards forwardly from the printing line; said arm carried on a slide mounted on said rod, and connected to a gage at the introductory side of the platen for the side edge of the card. 80
6. The combination with a revoluble platen, of a driving roll to run upon the surface of the platen at the delivery side thereof, card-feeding means operated by said driving roll, and a support on which said roll and feeding means are adjustable together along the platen. 85
7. The combination with a revoluble platen, of a driving roll to run upon the surface of the platen at the delivery side thereof, card-feeding means operated by said driving roll, a support on which said roll and feeding means are adjustable together along the platen, and means to regulate the pressure of the driving roll on the platen. 90
8. The combination with a revoluble platen, of a driving roll to run upon the surface of the platen at the delivery side thereof, a card-feeding roll operated by said driving roll, means to regulate the pressure of the driving roll on the platen, and a directrix leading from the printing line to the feeding roll; said rolls, pressure-regulating means and directrix adjustable together along the platen. 95
9. The combination with a revoluble traveling platen, of a driving roll to run upon the surface of the platen at the delivery side thereof, card-feeding means operated by said driving roll, and a guide fixed upon the framework of the machine in proximity to the front of the traveling platen, and extending toward said feeding means. 100
10. The combination with a revoluble platen, of means adjustable along the platen for feeding cards upon the delivery side of the platen, said feeding means comprising a driving roll to run upon the surface of the platen and a card feeding roll rotated by said driving roll, and means to press the card against the feeding roll. 110
11. The combination with a revoluble platen, of means adjustable along the platen for feeding cards upon the delivery side of the platen, said feeding means comprising a 115
12. The combination with a revoluble platen, of means adjustable along the platen for feeding cards upon the delivery side of the platen, said feeding means comprising a driving roll to run upon the surface of the platen and a card feeding roll rotated by said driving roll, means to press the card against the feeding roll, and a directrix leading from the printing line to the feeding roll. 120
13. In a typewriting machine, the combination with a revoluble platen, of a card-holding mechanism comprising a pair of driving rolls running upon the platen, card-feeding rolls running in contact with said driving rolls, and means opposed to said feeding rolls to coöperate therewith to feed the cards. 125
14. In a typewriting machine, the combination with a revoluble platen, of a card-holding mechanism comprising a pair of driving rolls running upon the platen, card-feeding rolls running in contact with said driving rolls, means opposed to said feeding rolls to coöperate therewith to feed the cards, and directrices extending from said feeding means toward the printing line on the platen. 130
15. In a typewriting machine, the combination with a revoluble platen, of a card-holding mechanism comprising a pair of driving rolls running upon the platen, card-feeding rolls running in contact with said driving rolls, means opposed to said feeding rolls to coöperate therewith to feed the cards, and means for regulating the pressure of said driving rolls against the platen. 135
16. In a typewriting machine, the combination with a revoluble platen, of a card-holding mechanism comprising a pair of arms adjustable along the platen, driving rolls running upon the platen and pivoted upon said arms, card-feeding rolls also pivoted upon said arms and running in contact with said driving rolls, and means opposed to said feeding rolls to coöperate therewith to feed the cards. 140
17. In a typewriting machine, the combination with a revoluble platen, of a card-holding mechanism comprising a pair of arms adjustable along the platen, driving rolls running upon the platen and pivoted upon said arms, card-feeding rolls also pivoted upon said arms and running in contact with said driving rolls, and means opposed to said feeding rolls to coöperate therewith to feed the cards; said arms having gages for the side edges of the cards at the introductory side of the machine. 145
18. In a typewriting machine, the combi-

- nation with a revoluble platen, of a card-holding mechanism comprising a pair of brackets mounted on a rod parallel with the platen for adjustment along the latter, arms 5 extending from said brackets, driving rolls running upon the platen, and pivoted upon said arms, and card-feeding rolls also pivoted upon said arms and running in contact with said driving rolls.
- 10 19. In a typewriting machine, the combination with a revoluble platen, of a card-holding mechanism comprising a pair of brackets mounted on a rod parallel with the platen for adjustment along the latter, arms 15 extending from said brackets, driving rolls running upon the platen and pivoted upon said arms, card-feeding rolls also pivoted upon said arms and running in contact with said driving rolls, and plates opposed to said 20 feeding rolls to coöperate therewith to feed the cards.
20. In a typewriting machine, the combination with a revoluble platen, of a card-holding mechanism comprising a pair of brackets mounted on a rod parallel with the platen for adjustment along the latter, arms 25 extending from said brackets, driving rolls running upon the platen and pivoted upon said arms, card-feeding rolls also pivoted upon said arms, and plates having directrices extending toward the printing line on the platen.
- 30 21. In a typewriting machine, the combination with a revoluble platen, of a card-holding mechanism comprising a pair of brackets mounted on a rod parallel with the platen for adjustment along the latter, arms 35 extending from said brackets, driving rolls running upon the platen and pivoted upon said arms, card-feeding rolls also pivoted upon said arms and running in contact with said driving rolls, plates opposed to said feeding 40 rolls to coöperate therewith to feed the cards, and adjustable means for regulating the pressure of said driving rolls against the platen.
22. In a typewriting machine, the combination with a revoluble platen, of a card-holding mechanism comprising a pair of slides mounted on a rod parallel with the platen for adjustment along the latter, arms 45 extending from said slides, driving rolls pivoted upon said arms and running upon the platen, card-feeding rolls also pivoted upon said arms and running in contact with said driving rolls, plates opposed to said feeding rolls to coöperate therewith to feed the cards, 50 said plates having directrices extending toward the printing line on the platen, and adjustable means for regulating the pressure of said driving rolls against the platen, comprising screws threaded through said arms to 55 bear against inclined surfaces upon said slides, the latter having gages at the introductory side of the machine for the side edges of the cards.
23. In a typewriting machine, the combination with a revoluble platen mounted on a carriage, of card-holding means including a stationary card guide in proximity to the platen near the printing point, a pair of card-feeding devices mounted on the carriage and including guide rolls to run upon the platen, 70 feed rolls operated by said guide rolls, and in position to be engaged by the card as it feeds up beyond said guide, and means coöperating with said feed rolls to engage said card on its opposite side to feed the same upwardly. 75
24. In a typewriting machine, the combination with a revoluble platen mounted on a carriage, of card-holding means including a stationary card guide in proximity to the platen near the printing point, a pair of card-feeding devices mounted on the carriage and including guide rolls to run upon the platen, 80 feed rolls operated by said guide rolls and in position to be engaged by the card as it feeds up beyond said guide, means coöperating with said feed rolls to engage said card on its opposite side to feed the same upwardly, and directrices extending from said feeding rolls toward the printing point. 85
25. In a typewriting machine, the combination with a revoluble platen mounted on a carriage, of card-holding means including a stationary card guide in proximity to the platen near the printing point, a pair of card-feeding devices mounted on the carriage and including guide rolls to run upon the platen, feed rolls operated by said guide rolls and in position to be engaged by the card as it feeds up beyond said guide, means coöperating 90 with said feed rolls to engage said card on its opposite side to feed the same upwardly, and directrices extending from said feeding rolls toward the printing point. 95
26. The combination with a revoluble platen, of a pair of driving rolls to run upon the surface of the platen at the delivery side thereof, feeding rolls driven by said driving rolls, and means coöperating with said feeding rolls to catch the side edges of the card to advance it past the printing line on the platen. 100
27. The combination with a revoluble platen, of a pair of driving rolls to run upon the surface of the platen at the delivery side thereof, feeding rolls driven by said driving rolls, means coöperating with said feeding rolls to catch the side edges of the card to advance it past the printing line on the platen, and means to regulate the pressure of each driving roll upon the platen independently of the other. 105
28. The combination with a revoluble platen, of a pair of driving rolls to run upon the platen, 110

the surface of the platen at the delivery side thereof, feeding rolls driven by said driving rolls, means coöperating with said feeding rolls to catch the side edges of the card to 5 advance it past the printing line on the platen, directrices leading from the printing line to the feeding rolls, and a card guide mounted upon the machine frame in proximity to the printing line; said platen 10 mounted upon a carriage to travel past said guide.

29. The combination with a revoluble platen, of a pair of sets of card-feeding devices, each set comprising a roll to run upon 15 the surface of the platen at the delivery side thereof, a card-feeding roll operated by said driving roll, and means to press the side edge of the card against the feeding roll.

30. The combination with a revoluble 20 platen, of a pair of sets of card-feeding devices, each set comprising a roll to run upon the surface of the platen at the delivery side thereof, a card-feeding roll operated by said driving roll, and means to press the side 25 edge of the card against the feeding roll; said sets being adjustable toward and away from each other along the platen.

31. In a typewriting machine, the combi-

nation with a revoluble platen and a platen frame, of a rod mounted on the platen frame 30 and extending along the platen, a pair of arms extending from said rod toward the printing line on the platen, driving rolls on said arms to run upon the surface of the platen, feeding rolls also mounted on said 35 arms and operated by said driving rolls, and means coöperating with said feeding rolls to catch the side edges of the card to advance it from the printing line.

32. In a typewriting machine, the combination with a revoluble platen and a platen frame, of a rod mounted on the platen frame 40 and extending along the platen, a pair of arms extending from said rod toward the printing line on the platen, driving rolls on 45 said arms to run upon the surface of the platen, feeding rolls also mounted on said arms and operated by said driving rolls, and means coöperating with said feeding rolls to catch the side edges of the card to advance 50 it from the printing line; said arms adjustable toward and from each other.
